(57) **CLAIM**

The ornamental design for a lavatory, as shown and described.

DESCRIPTION

FIG. 1 is a top and front perspective view of a lavatory showing our new design;

FIG. 2 is a top plan view shown on an enlarged scale thereof;

FIG. 3 is a front elevation view shown on an enlarged scale thereof;

FIG. 4 is a right elevation view shown on an enlarged scale, the left side being a mirror image thereof; and,

FIG. 5 is a bottom plan view shown on an enlarged scale thereof.

The broken lines showing of environmental structure are for illustrative purposes only and form no part of the claimed design.
